CLAIM

The ornamental design for a connector, as shown and described.

DESCRIPTION

FIG. 1 is a perspective view of a connector showing my new design;

FIG. 2 is a frontal elevational view thereof;

FIG. 3 is a top plan view thereof;

FIG. 4 is a bottom plan view thereof;

FIG. 5 is a right side view thereof; and,

FIG. 6 is a left side view thereof.

The connector portion shown in broken lines is for illustrative purposes only and forms no part of the claimed design.
